UNITED STATES PATENT OFFICE.

ANDREW W. GRAHAM, OF BUFFALO, NEW YORK, ASSIGNOR TO CITY TRUST CO.
BRANCH OF THE MARINE TRUST CO. OF BUFFALO, TRUSTEE, OF BUFFALO, NEW
YORK.

MATCH PACKET OR CARTON.

1,417,729.

Specification of Letters Patent. Patented May 30, 1922.

Application filed December 8, 1920. Serial No. 429,239.

To all whom it may concern:

Be it known that ANDREW W. GRAHAM, a citizen of the United States of America, residing at Buffalo, in the county of Erie 5 and State of New York, has invented certain new and useful Improvements in Match Packets or Cartons, of which the following is a specification.

This invention relates to packets or cartons 10 suitable for containing matches and other like articles and is peculiarly adapted to be used as an advertising medium.

One important object of the invention is to provide an improved general construction of 15 devices of this character and especially to improve and simplify the construction of match packet disclosed in my prior Patent Number 1,351,242, patented August 31, 1920.

A second important object of the invention 20 is to provide an improved form of packet or carton constructed from a single sheet of cardboard or the like.

A third important object of the invention 25 is to provide an improved double packet or carton constructed from a single sheet of cardboard or the like.

A fourth important object of the invention 30 is to provide an improved double packet having leaves folding into the packet for carrying matches, the whole being constructed of a single sheet of cardboard or the like.

A fifth important object of the invention 35 is to provide an improved packet of this class having improved means for holding the packet normally shut, said means also functioning to hold the packet attached to a box or package as of cigarettes.

With the above and other objects in view, 40 as will be hereinafter apparent, the invention consists in general of certain novel details of construction and combinations of parts hereinafter fully described, illustrated in the accompanying drawings and 45 specifically claimed.

In the accompanying drawings like characters of reference indicate like parts in the several views, and:—

Figure 1 is a perspective view of one form 50 of the packet applied to a package of cigarettes.

Figure 2 is a plan of the blank from which this form is made.

Figure 3 is a cross section through this 55 form of the packet showing a novel arrange-

ment of means for both holding the packet closed and attaching it to a package of cigarettes or the like.

Figure 4 is a perspective view of the form 60 shown in Figure 3.

Figure 5 is a perspective view of a double packet constructed in accordance with this invention.

Figure 6 is a plan of the blank from which 65 the packet shown in Figure 5 is formed.

Figure 7 is a perspective view of a second form of double packet constructed in accordance with this invention.

Figure 8 is a plan of the blank from which 70 the packet shown in Figure 7 is formed.

Figure 9 is a section through a still further modification.

Figure 10 is a detail showing a modification wherein the material forming the carton is bent and pressed to form a channel 75 adapted to receive the butts of matches.

In all of the embodiments of the invention herein illustrated each packet is formed from a sheet of cardboard or the like and the blank consists of two or more parts defined each from each by a fold line whereby the adjacent parts have hingedly connected relation. In every instance it will be seen that at least one of the connected portions is stamped or pressed to form a shallow, tray 85 like part.

In the form shown in Figures 1 and 2 this shallow tray is shown at 10 and on one edge thereof is hingedly carried a flat member 11 which may be called the attaching flap or 90 back flap. On the other edge is hingedly carried a flap 12 carrying matches 13. The back of the part 11 may be coated with a suitable adhesive so that it may be attached to a match packet P or a similar part 11 of 95 another packet by means of such adhesive. Moreover the parts 10 and 11 are connected by an elastic strand 14 so as to hold the cover closed under normal conditions. It will be obvious that, if desired, the part 12 100 can be omitted and the flap 11 glued or otherwise secured to a second packet to form a double packet resembling that shown in Figure 5.

In the form just described the elastic 105 strand 14 may be positioned through slits 15 formed at the junction of the parts 10 and 11 as clearly shown in Figures 1 and 2, these slits terminating in eyes 16 offset to one side of the slits. The form shown in Figures 3 110

and 4 is very similar to that just described except that the part 12 is omitted and the matches 13 are fastened directly to the part 11. Moreover in this part the elastic strand 5 has its ends separate, one end of each strand being secured to the part 11 through a hole 17 near its edge while the other end passes through the hole 16 in part 11 and through the similar hole in the part 10 and is there 10 secured. By this arrangement a match packet P may be inserted as shown in Figures 3 and 4 so that this elastic member serves the double function of holding the cover closed and of holding the packet in position on a 15 package of cigarettes or the like.

In the form shown in Figures 5 and 6 the blank consists of two of the shallow, tray like portions 10 and the flap portion 11 connects the two being joined thereto by hinged 20 lines 18. In this form it will be seen from Figure 6 that the connective side of one portion 12 is on one side of the blank while the connective side of the other portion 10 is on the other side of the blank.

25 In the form shown in Figures 7 and 8 the form is identical with that of Figure 5 except that end flaps 19 are also employed so that the matches may be secured thereto. It is especially to be noted that the form of 30 Figure 5 provides no less than four surfaces on each to display advertising matter while the form of Figure 7 provides no less than eight such display surfaces.

In the form shown in Figure 9 the part 35 11 is eliminated or rather modified to form a second shallow, tray-like portion 10, the two portions being defined by a fold line 20 forming a hinge. Tabs 21 may be applied to the edges of the proper parts wherever 40 desired and all of the forms may be provided with suitable means to hold them yieldably closed although such means are not shown in each instance, being exemplified clearly in the forms of Figures 1 to 4 45 inclusive.

There has thus been provided a simple and efficient device of the kind described and for the purpose specified.

It is obvious that many minor changes may be made in the form and construction 50 of the invention without departing from the material principles thereof. It is not therefore deemed necessary to confine the invention to the exact form herein shown and described but it is wished to include all such 55 as properly come within the scope claimed.

Having thus described the invention what is claimed as new, is:—

1. In a carton, a pair of spaced body portions formed of cardboard like material and 60 each pressed to form a shallow tray, a flap between said body portions, said flap and body portions being formed integrally and having hinge like connections, and other flaps likewise formed integrally with said 65 body portions, each having hinge like connection with a respective body portion said body portions being folded one on one side and the other on the other side of first mentioned flap whereby the flap forms a closure 70 for each of said body portions.

2. In a carton, a pair of shallow, tray like body portions facing in opposite directions, and a flap hingedly connected from one edge of one body portion to the opposite edge of 75 the other body portion said body portions being folded one on one side and the other on the other side of said flap whereby said flap constitutes a closure for the body portions common to both of them.

3. In a carton, a body portion formed of a piece of cardboard like material pressed to form a shallow, tray like body, a cover portion formed integrally with the body portion and hingedly connected thereto, and a plurality of elastic strands each having one end connected to the cover adjacent its free edge and the other end passing through the cover adjacent the body and connected to the body whereby the strands yieldably hold the parts 90 closed and whereby that portion of the strands crossing the cover forms means for attaching the device to a package.

In testimony whereof I affix my signature.

ANDREW W. GRAHAM.
